UNITED STATES PATENT OFFICE.

GEORGE CORNET, OF SAN FRANCISCO, CALIFORNIA.

OS-CALCIS METATARSAL-ARCH SUPPORTER.

1,219,257.

Specification of Letters Patent. Patented Mar. 13, 1917.

Application filed July 1, 1916. Serial No. 107,180.

To all whom it may concern:

Be it known that I, GEORGE CORNET, a citizen of the United States, residing in the city and county of San Francisco and State of California, have invented new and useful Improvements in Os-Calcis Metatarsal-Arch Supporters, of which the following is a specification.

This invention relates to an os calcis metatarsal arch supporter.

The object of the present invention is to provide a foot corrector consisting of a plate formed by taking a plaster-of-Paris impression from the natural foot so that every articulation will fit perfect and to so extend the plate that it will not only form a support for the several arches of the foot, such as the longitudinal arch, the anterior metatarsal arch and the transverse arch but also the os calcis or heel of the foot.

Further objects will hereinafter appear.

The invention consists of the parts and the construction and combination of parts as hereinafter more fully described and claimed, having reference to the accompanying drawings in which—

Figure 1 is a perspective view of the supporter.

Fig. 2 is a central, longitudinal section 30 through the supporter, showing its position with relation to the bones of the foot.

The foot proper consists of twenty-six articulated bones and joints, each being joined to the other by highly tensified membranes 35 known as ligaments and muscles. The frame work of the human muscles and tendons passing from the leg and heel, forward to the foot is so arranged as to permit considerable movement to each joint.

40 The bones of the foot commencing at the os calcis (heel bone) forward to the metatarsal and phalangeal articulations as shown in Fig. 2 represent the longitudinal arch. The os calcis is the largest bone of the foot, 45 It measures about $2\frac{1}{2}$ inches long and is quite thick. Next to this is the astragalus, scaphoid and cuneiform, and forward of the internal cuneiform are the metatarsals.

The five metatarsals articulate forward 50 with the phalanges (bones of the toes), fourteen in number. The weight of the body is transmitted to the foot through the tibia and fibula, which articulate on the astragalus and os calcis. The astragalus (keybone of the arch) carries practically the entire weight of the body.

To promote the elasticity of the foot and to enable this collection of bones thus articulated (or joined) to properly support the weight of the body, they are arranged in 60 the form of arches or domes.

These arches are held together by ligaments and muscles and long tendons of the muscles in the calf of the leg. Free action is procured and in place of the foot being 65 rigid in action, it is springy and highly elastic.

The longitudinal arch, the most important one, extending from the heel forward to first metatarsal-phalangeal joint, takes 70 in the tarsal and metatarsal bones from the inner side. It is this arch where flat foot develops. The anterior metatarsal arch extending crosswise of the foot between the first and fifth metatarsal (great and little 75 toe) is formed by the heads of the metatarsal bones. When these bones drop great pain and trouble is noted. Then of less importance is the outer longitudinal arch and the transverse arch at the heels of the metatarsals and the three cuneiform and cuboid bones.

The structure of the foot from a mechanical point of view is perfected, as each time the weight of the body is thrown suddenly 85 on the foot, the supporting muscles and ligaments yield sufficiently to permit considerable movement between the individual bones, thus permitting the several arches to spring or yield as weight is applied or removed. When the tone and strength of the ligaments become impaired, due to strains or stretching of the ligaments, and the muscles are unable to do their work normally on account of pressure and strain, a 90 condition will result, known as "pes planus" or flat foot. This deformity, strictly speaking, is not only a flattening of the foot as most people think, but also consists in the settling and twisting of the bones of the 95 arch. The purpose of the present invention is to provide means for not only supporting the several arches of the foot but also to support the os calcis or heel of the foot in such a manner that too much yielding or 100 springing of the several arches is to a certain extent prevented. This is accomplished by making a plaster-Paris cast from the foot to be treated, then forming a thin non-yielding metal plate A from the impression secured, in this manner permitting every articulation to be perfectly fitted. By referring to 110

Figs. 1 and 2, it will be seen that the heel section of the plate is extended upwardly and around the heel of the foot as at 3. This forms a natural recess or support for the os calcis or heel and cooperates with the other arches formed in the plate, to prevent too much flexing or yielding of the arches, particularly the longitudinal arch. The extension provided by forming the plate to inclose the lower part of the heel of the foot forms a perfect support for same, which relieves the os calcis to a certain extent of too much pressure. It also at the same time, forms a socket or recess for the heel, which holds it in a rigid position, in this manner preventing sliding movement of the heel when weight is placed on the foot and the longitudinal arch yields. The distance between the os calcis indicated at 4, and the 10 metatarsal and phalangeal articulations shown at 5 is thus kept constant, in this manner supporting the astragalus or middle cuneiform bones from settling or causing a flat foot, as heretofore described. The plate being formed from a plaster cast of the foot fits the exact curvatures of the arches and as spreading of the longitudinal arch is prevented by reason of the construction provided, it will be seen that the other arches 20 will be retained in position and perfectly supported. In other words, the foot proper is prevented from spreading out over the plate or the equilibrium disturbed by displacement of the supporting points. The 25 plate has a transversely flat forward bottom portion (Fig. 1) which rests upon the insole of the shoe and holds the plate firmly in position.

against rocking sidewise, thus enabling the foot to rest firmly in position within the plate.

The plate proper may be lined with leather as indicated at 6, to produce as smooth and comfortable a surface as possible but the materials and finish may otherwise be such as the judgment and experience of the manufacturer may dictate.

I wish it understood that various changes in form, proportions and minor details of construction may be resorted to within the scope of the appended claim, and that I do not wish to limit myself to the specific design and construction here shown.

Having thus described my invention, what I claim and desire to secure by Letters Patent is—

A heel and arch supporter comprising a metal plate formed to fit the arches of the foot, having its rear end bent to form a heel socket for surrounding the lower side and back portions of the heel, and having its forward end arranged to terminate beneath the metatarsal and phalangeal articulations of the foot and formed flat transversely to provide a broad seating at its forward end to withstand any lateral wobbling of the heel end which latter point of support is comparatively narrow.

In testimony whereof I have hereunto set my hand in the presence of two subscribing witnesses.

GEORGE CORNET.
